ROTARY IMPACT PIPE CUTTER

Robert M. D'Arcy, Dallas, Tex.

Application September 3, 1948, Serial No. 47,635

3 Claims. (Cl. 164—0.4)

1

This invention relates to pipe cutters operated from within the pipe to be cut, and particularly to a pipe or casing cutter caused to rotate by delivering impacts to a portion thereof.

The main object of my invention is to provide a pipe or casing cutter for the casings of oil wells and the like which is capable of cutting the casing at a predetermined depth from within the casing by jarring the device or delivering a series of impacts thereto.

Another object is to provide means for positioning such a cutter in a selected position within the well casing or pipe and causing cutter means to project out into the cutting position with respect to said pipe.

A further object is to provide such a cutter with means for converting axial jarring and impact into controlled rotation of the cutter members in effective cutting direction.

It is also an object to have a cutter of the indicated character which is self-contained and effective to operate out in the field without resort to makeshift or temporary expedients.

Other objects and advantages of my invention will appear in further detail as the specification proceeds.

In order to facilitate ready comprehension of this invention for a proper appreciation of the salient features thereof, the invention is illustrated on the accompanying drawings forming part hereof, and in which:

Figure 1 is a vertical section through an oil well pipe or casing into which a rotary impact pipe cutter made according to the invention has been introduced preparatory to cutting off the length of said pipe or casing;

Figures 2a, 2b and 2c are all parts of a vertical section of the pipe cutter embodying the invention, being shown on an enlarged scale with Figure 2a showing the lowest section, 2b showing the intermediate section, and 2c showing the upper end or uppermost section of the pipe or casing cutter.

The same reference numerals indicate the same or like parts throughout.

In oil fields, it occasionally occurs that an oil well becomes exhausted and useless, or for some reason the well is no longer used. As a well of this type is usually lined with a pipe or casing of metal, a deep well thus represents a considerable investment in metal in the casing. In fact, the casing, if in good condition, may largely be used again, and in any event, salvage of as much of the casing as possible is always desirable. Obviously, this means that the casing should be

2

cut off as far down in the well as practicable, so that the portion thus cut off may be raised to the surface. Of course, I am aware that certain expedients have heretofore been tried, but results have been rather limited.

Upon considering this problem carefully, it has occurred to me that a purely rotary cutter to be lowered far down into an oil well casing is not practical, while on the other hand, if vibration or jarring about or near the surface will suffice to cause a cutting action, it should be possible to cut the pipe or casing at a much greater depth than has heretofore been possible, so that as much of the casing is salvaged as then becomes practical. As a result, I have found it quite feasible to produce a rotary impact pipe cutter which derives its rotation from direct impacts or jarring of one end thereof, as will now be described more fully.

20 Hence, in the practice of my invention, and referring again to the drawings, an oil well casing 3 extending down into the ground 4 is first provided with a location plug 5 of more or less conventional construction provided with a small bore 6 and with a pair of opposite grooves 7, 7. Before describing the manner in which the present casing cutter is lowered into the tube or casing 3, it will perhaps serve best to described the device in detail.

25 As best seen in Figure 2a, at the lower end of the device is a feeder head 8 preferably conical in form and having an upper cylindrical portion 9 from which project a pair of radially-extending butterflies or flanges 10, 10, the head being integral with an upwardly-extending shank 11. The upper end of the shank 11 is threaded at 12 and screwed into a wedge or converter feed block 13. The wedge or converter feed block 13 is slidably disposed within a tool holder 14 within the hollow interior of which are a pair of opposite vertical grooves 15, 15 into which a pair of corresponding ribs 16, 16 upon the block 13 project in slidable manner. At the lower end the tool holder has a reduced neck portion 17, and this terminates at the bottom in a flange 18. Beneath the lower end of the tool holder 14 is fixed a collar 19 by means of a set screw 20 upon the shank 11, the latter projecting rotatably through a bore 21 in the neck 17 and into the interior of the tool holder within which a second collar 22 fixed on the upper portion of the shank beneath the threaded portion 12 thereof by means of a set screw 23 rests rotatably on the bottom 24 of said interior. The shank 11 thus projects rotatably up through the bore 21 in neck 17 of tool holder

40 45 50 55

14 and rotation thereof with respect to the tool holder will cause it to be gradually unscrewed from the block 13 with consequent raising of the block along the grooves 15, 15 in the interior 25 of said tool holder. The effect of such raising of block 13 will presently be noted in more detail. Surmounting the tool holder 14 is an upper tool holder 26 complementary to the lower tool holder 14 and having a large internal bore 27, while at the lower end thereof it is provided with a pair of radially-extending slots 28, 28 serving to locate and guide a pair of radially-extending cutting tools 29, 29, each of which has a pin 30 affixed thereon, both pins being interconnected by means of a tension spring 31 tending to draw the tools together within the outline of the tool holders 14 and 26. The latter are secured together by a group of long vertical bolts 32, 32, so that both tool holders together will serve as a tool-holding unit. Within the inner chamber 25 of the lower tool holder 14 is located an upwardly-pointed wedge or converter 33 engaging slidably against a pair of inner inclined ends 34 of the cutting tools 29, 29, while the lower end 35 of the wedge 33 rests upon the feed block 13.

The arrangement is such that if the lower feeding head 8, 9 is seated in the plug 5 within the casing 3, as per Figure 1, and the side flanges or butterflies 10, 10 engage in the grooves 1, 1 to prevent the head from rotating, and then some means is applied to the tool-holder assemblage to rotate the latter, it is obvious that due to the fact that the feed block 13 will be forced to rotate with the tool-holder assemblage due to its ribs 16, 16 engaging in the grooves 15, 15 within chamber 25 of the lower tool holder, this block will gradually unscrew from the upper end 12 of the shank 11, thereby gradually raising the block 13 and with it the wedge 33, which will, of course, gradually wedge the two cutting tools 29, 29 apart so that the outer ends thereof will engage against the sides of the well casing 3 and begin to cut into the same, and when such rotation is continued, the tools will be fed increasingly farther out until such feeding of the tools and simultaneous rotation will cause the casing to be cut through after but a few revolutions.

At this stage attention is now to be directed to the means for causing rotation of the tool holder assembly for effecting the mentioned cutting of the well casing. At the upper end of the upper tool housing or holder member 26, the bore 27 is reduced to a smaller bore 36 providing a shoulder 37, and upon the upper end of the same member 26 is a ratchet 38 capable of interengaging with a corresponding downwardly-projecting ratchet 39 of an upper rotatable ratchet section 40. The two rachets 38 and 39 are retained in aligned assembly by means of a ratchet clutch member 41 slidably fitting in the bore 36 within lower ratchet 38, the lower end of the clutch member 41 being provided with a head 42 normally engaging against the shoulder 37 and being prevented from dropping down into the bore 27 by means of a stop ring 43 expanded into a groove 44 in the wall of bore 27 but a short distance below said head 42. The upper end of the clutch member 41 is also provided with a cylindrical head 45 slidable in the bore 46 in the lower end of the upper clutch member 40, but at a predetermined point spaced below the head 45 is a cushioning collar of fiber or other material 47 fixed within the bore 46 by means of a set screw 48 providing in the distance between the head 45 and the upper edge of said collar 47 ample clearance for

the clutch member 41 to be moved with the tool-holder assembly downward to release the clutch members 38 and 39 temporarily from each other, this being a necessary part of the movement for operating the present casing cutter, as will appear later on.

Loosely surrounding the lower portion of the upper ratchet member 40 is a group of slip holders 49, 49 retained in association by means of a ring 50 secured thereto. Pivoted mounted at 51, 51 upon the upper ends of the slip holders 49, 49 are a corresponding number of tubing slips 52, 52 provided with the gripping teeth 53, 53 upon the upper outer sides thereof, and at the lower ends provided with springs 54 enveloping the pivot members 51 engaging against the holders 49 and the lower portions of said members 52 in such fashion as to tend to swing the slips inward toward the clutch member 40. Cooperating with these slips is a lower tapered ring 55 slidably surrounding the intermediate portion of clutch member 40 and having a shoulder recess 56 about the upper end thereof to which is fitted a tube 57, the lower end of which is secured to the tapered member 55 by means of screws 58, 58. The tapered hollow member 55 forms a slip expander upon the lower end of the tubular housing 57 and simultaneously a lower retainer for the upper ratchet member 40 inasmuch as the latter is provided with an upper flange 59 for which the upper end 60 of member 55 forms an effective stop, as best seen in Figure 2b. The mentioned tubular housing 57 extends upwardly a predetermined distance to terminate just below the upper end of the shank 61 to be further explained, and within said upper end of the housing is fixed a collar 62 within which a fiber seal or other material in the form of a washer or smaller collar 63 is located and slidably mounted on the mentioned shank 61. At the lower end of shank 61 just mentioned is attached a housing 64 which is likewise tubular and within the lower end of which are secured a pair of inwardly-directed groove runners 65, 65 by means of screws 66, from which the inwardly-projecting, groove-engagement members 67, 67 extend integrally into a pair of opposite helical grooves 68, 68 in the sides of an upwardly-extending feed shaft 69 extending rigidly from the upper end of the upper clutch member 40 above the upper flange 59 thereof and terminating at the upper end in a flange 70 having a range of movement almost the distance between the upper closed end 71 by which the shank 61 is connected to the tubular housing 64 and the upper ends of the groove runners 65. The upper end of the mentioned shank 61 terminates in a threaded portion 72 adapted to be connected to a standard jarring device in order to provide vertical jarring movements and impacts to shank 61 and thereby to tubular housing 64 with its groove runners 65.

It is self-evident that vertical movement of the shank 61 and housing 64 with its mentioned groove runners 65 will be converted to rotary movements of the feed shaft 69 in both directions due to the helical form of the groove 68.

If the apparatus is now to be lowered into the well casing 3 in order to cut the same, the jarring device is, of course, connected to the threaded upper end 72 of shank 61, the jarring device including a weighted jarring rod, while a wire line is connected to the cutter assemblage and the housings in order to lower the assemblage into the well, and when the proper depth has been determined, the housing 57 is allowed to come

to rest with its lower slip-expanding, conical portion 55 engaging against the inner sides 73 of the slip members 52, causing the teeth 53 upon each to engage in the wall of casing 3, so that housing 57 is held firmly immovable within the well casing. It is, of course, simultaneously determined that the lower locating head 8, 9 comes to rest on the plug 5 previously located at the proper depth within the casing, and the two wings or flanges 10, 10 caused to engage in the grooves 7, 7 in the interior 6 of the nut to prevent rotation thereof when the apparatus is substantially ready for operation. Upon the jarring device being started to transmit the impact thereof down through shank 61, the groove runners within the lower end of tubular member 64 will be caused to ride downward in the grooves 68, 68 with their projections 67, 67 gradually rotating the feed shaft 69. The tubular member 64 is thus allowed to travel downward a distance within the tubular housing 57, meanwhile rotating feed shaft 69, as already mentioned, with the result that the tool holders 14 and 26 forming the tool-holder assemblage simultaneously rotated through the interengagement of ratchets 38 and 39, causing gradual unscrewing of the thread 22 on shank 11 from within the feed block 13 and consequent rise of the wedge 33 and separation of the cutting tools 29, 29 and projection thereof radially out through the slots 28, 28 to begin to cut into the wall of casing 3. One descent of the tubular member 64 will only produce limited rotation of the feed shaft 69 so that the shank 61 with the jarring device and tubular member 64 are again raised causing reverse rotation of feed shaft 69 with simultaneous raising of the ratchet member 40, and with it separation of ratchets 38 and 39 and the raising of internal collar 41 against the bottom of the head 45 on the upper end of clutch member 41, with the result that the reverse rotation is not transmitted to the tool-holder assemblage. Subsequently, the shank 61 and tubular member 64 are again allowed to descend, also allowing feed shaft 69 and the upper clutch member 40 connected to the bottom thereof to lower so that the clutch members 38 and 39 again become engaged, and jarring of the upper shank 61 will again cause the inner tubular housing 64 to descend with its groove runners 64 and 65 and their projections 67, 67 in the groove 68 again taking effect to rotate feed shaft 69, with consequent further rotation of the tool-holder assemblage and tools 29 and further feeding of the latter outward while cutting into the wall of well casing 3. This raising and lowering of the mentioned upper shank 61 and its internal housing 64 is repeated until a sufficient number of revolutions of the tool-holder assemblage 14, 26 with tools 29, 29 has occurred to completely cut through the casing 3. Preparatory to removing the cut portion of the casing, the cutting device thus far described must, of course, be raised and completely removed from the casing.

Obviously, when the housing 57 has raised, as well as the shank 61, the lower conical end 55 of housing 57 will be drawn up out of contact with slips 52, allowing the teeth 53 thereof to disengage from the sides of the housing.

It should be mentioned at this point that during the cutting operation which has, of course, proceeded to the point where the cutting tools 29 have completely cut through the well casing, the wedge or converter which is actually a floating member has, of course, been gradually fed upward

until the sides 74, 74 have actually passed the lower inner inclined faces 34 of the tool members 29, so that the upper inclined surfaces 75, 75 of said cutting tools will begin to engage the lower inclined surfaces 76, 76 of the wedge member 33, and due to the presence of spring 31, the cutting tools 29 will be drawn together and the wedge forced upward into the bore 27 of upper tool holder 26. This action, of course, withdraws the tools 29 within the outline of the tool-holder assemblage 14 and 26 and allows the entire cutter assembly to be withdrawn from well casing 3.

Should I desire to do so, I may add further slips to engage within the tubular casing 3, and, of course, the proportions and arrangements of the parts may be varied so long as the jarring principle of dropping the weights along the length of the jars and transmitting the impacts to the upper shank 61 is maintained. Thus, the downward movement of the inner housing 64 causes rotation of the feed shaft which is transmitted to the tool holders and the tools with the effect of cutting the casing of the well.

Manifestly, variations other than those noted may be resorted to and parts and features may be modified or used without others within the scope of the appended claims.

Having now fully described my invention, I claim:

- 30 1. A rotary impact pipe cutter adapted for insertion into the pipe or casing to be cut, including a pair of tool-holder members secured together one above the other in axial alignment to form a rotatable tool-holder assembly, the lower tool-holder member having an upwardly-open, central chamber with vertical guide grooves in the sides thereof, the upper tool-holder member having a downwardly-open central chamber communicating with the central chamber of the lower tool-holder member, the tool-holder assembly having a pair of opposite cutting tool slots extending radially outward from the resulting hollow interior therein, a pair of cutting tools disposed radially slidable in the slots with the inner ends thereof extending into said hollow interior, a vertically-movable feed block located in the central chamber of the lower tool-holder member with projections extending slidably into the guide grooves therein, the feed block having a downwardly-open, threaded axial hole therein and said lower tool-holder member having a vertical central bore through the lower end aligned with the threaded axial hole of the feed block, a shaft forming a shank having a guide means upon the lower end for engaging with a placing plug or the like to prevent rotation thereof and extending rotatably up through said vertical central bore and having the upper end threaded and engaging in the threaded hole in said feed block, a pair of stop members fixed upon the shank above and below the lower end of said lower tool-holder member to prevent axial movement of said shank with respect to said lower tool-holder member, an upwardly-directed wedge or converter supported upon said feed block with the apex portion disposed between the inner ends of said cutting tools in effective position to feed them radially outward from the tool-holder assembly against the casing to cut the latter upon rotation of said tool-holder assembly upon said shank, a spring biasing both tools inwardly toward each other to withdraw them into the outline of said tool-holder assembly when said feed block has been at least partly unscrewed from the upper threaded end of said shaft and has raised said wedge upwardly past the in-

ner ends of said cutting tools into the bore of the upper tool-holder member, a one way ratchet upon the upper end of the latter, an upper corresponding ratchet member adapted to engage with the one-way ratchet, an axial lost-motion connection between the ratchet and upper ratchet member allowing limited axial separation of the one from the other, an upwardly-extending feed shaft projecting rigidly from the upper end of said upper ratchet member and having helical grooves cut upon the feed shaft, a vertically-movable tubular member surrounding the latter, a pair of groove runners secured upon the inside of the latter movable tubular member having projections slidably engaging in the helical grooves in said feed shaft, and an upwardly-extending shank fixed upon the upper end of said movable tubular member and having the upper end thereof threaded for connection with a jarring device in order to cause downward travel of said movable tubular member about said feed shaft and travel of the groove runners along the helical grooves in the latter to cause a one-way rotation of said feed shaft and consequent rotation of said tool-holder assembly through the ratchet and upper ratchet member.

2. A rotary impact pipe cutter adapted for insertion into the pipe or casing to be cut, including a pair of tool-holder members secured together one above the other in axial alignment to form a rotatable tool-holder assembly, the lower tool-holder member having an upwardly-open, central chamber with vertical guide grooves in the sides thereof, the upper tool-holder member having a downwardly-open central chamber communicating with the central chamber of the lower tool-holder member, the tool-holder assembly having a pair of opposite cutting tool slots extending radially outward from the resulting hollow interior therein, a pair of cutting tools disposed radially slidably in the slots with the inner ends thereof extending into said hollow interior, a vertically-movable feed block located in the central chamber of the lower tool-holder member with projections extending slidably into the guide grooves therein, the feed block having a downwardly-open, threaded axial hole therein and said lower tool-holder member having a vertical central bore through the lower end aligned with the threaded axial hole of the feed block, a shaft forming a shank having a guide means upon the lower end for engaging with a placing plug or the like to prevent rotation thereof and extending rotatably up through said vertical central bore and having the upper end threaded and engaging in the threaded hole in said feed block, a pair of stop members fixed upon the shank above and below the lower end of said lower tool-holder member to prevent axial movement of said shank with respect to said lower tool-holder member, an upwardly-directed wedge or converter supported upon said feed block with the apex portion disposed between the inner ends of said cutting tools in effective position to feed them radially outward from the tool-holder assembly against the casing to cut the latter upon rotation of said tool-holder assembly upon said shank, a spring biasing both tools inwardly toward each other to withdraw them into the outline of said tool-holder assembly when said feed block has been at least partly unscrewed from the upper threaded end of said shaft and has raised said wedge upwardly past the inner ends of said cutting tools into the bore of the upper tool-holder member, a one-way

ratchet upon the upper end of the latter, an upper corresponding ratchet member adapted to engage with the one-way ratchet, the ratchet having an upwardly-open bore of smaller diameter than the main bore in said upper tool-holder member and the upper ratchet member also having a downwardly-directed bore therein, a ratchet-connecting member extending down into the upwardly-open bore in the ratchet and having a flange upon the lower end forming a retaining means within the main bore in said upper tool-holder member, the ratchet-connecting member extending up into the downwardly-directed bore in said upper ratchet member and having a flange upon the upper end thereof which is axially slidable in the same bore, a stop collar secured in the lower portion of the latter bore about said ratchet-connecting member and serving as a cushion member and stop for limiting downward movement of said ratchet-connecting member to provide ample clearance for separation of the ratchet and upper ratchet member, an upwardly-extending feed shaft projecting rigidly from the upper end of said upper ratchet member and having helical grooves cut upon the feed shaft, a vertically-movable tubular member surrounding the latter, a pair of grooved runners secured upon the inside of the latter movable tubular member having projections slidably engaging in the helical grooves in said feed shaft, and an upwardly-extending shank fixed upon the upper end of said movable tubular member and having the upper end thereof threaded for connection with a jarring device in order to cause downward travel of said movable tubular member about said feed shaft and travel of the groove runners along the helical grooves in the latter to cause a one-way rotation of said feed shaft and consequent rotation of said tool-holder assembly through the ratchet and upper ratchet member.

3. A rotary impact pipe cutter adapted for insertion into the pipe or casing to be cut, including a pair of tool-holder members secured together one above the other in axial alignment to form a rotatable tool-holder assembly, the lower tool-holder member having an upwardly-open, central chamber with vertical guide grooves in the sides thereof, the upper tool-holder member having a downwardly-open central chamber communicating with the central chamber of the lower tool-holder member, the tool-holder assembly having a pair of opposite cutting tool slots extending radially outward from the resulting hollow interior therein, a pair of cutting tools disposed radially slidably in the slots with the inner ends thereof extending into said hollow interior, a vertically-movable feed block located in the central chamber of the lower tool-holder member with projections extending slidably into the guide grooves therein, the feed block having a downwardly-open, threaded axial hole therein and said lower tool-holder member having a vertical central bore through the lower end aligned with the threaded axial hole of the feed block, a shaft forming a shank having a guide means upon the lower end for engaging with a placing plug or the like to prevent rotation thereof and extending rotatably up through said vertical central bore and having the upper end threaded and engaging in the threaded hole in said feed block, a pair of stop members fixed upon the shank above and below the lower end of said lower tool-holder member to prevent axial movement of said shank with respect to said lower tool-holder member, an upwardly-directed wedge or converter supported upon said feed block with the apex portion disposed between the inner ends of said cutting tools in effective position to feed them radially outward from the tool-holder assembly against the casing to cut the latter upon rotation of said tool-holder assembly upon said shank, a spring biasing both tools inwardly toward each other to withdraw them into the outline of said tool-holder assembly when said feed block has been at least partly unscrewed from the upper threaded end of said shaft and has raised said wedge upwardly past the inner ends of said cutting tools into the bore of the upper tool-holder member, a one-way

wardly-directed wedge or converter supported upon said feed block with the apex portion disposed between the inner ends of said cutting tools in effective position to feed them radially outward from the tool-holder assembly against the casting to cut the latter upon rotation of said tool-holder assembly upon said shank, a spring biasing both tools inwardly toward each other to withdraw them into the outline of said tool-holder assembly when said feed block has been at least partly unscrewed from the upper threaded end of said shaft and has raised said wedge upwardly past the inner ends of said cutting tools into the bore of the upper tool-holder member, a one-way ratchet upon the upper end of the latter, an upper corresponding ratchet member adapted to engage with the one-way ratchet, an axial lost-motion connection between the ratchet and upper ratchet member allowing limited axial separation of the one from the other, an upwardly-extending feed shaft projecting rigidly from the upper end of said upper ratchet member and having helical grooves cut upon the feed shaft, a vertically-movable tubular member surrounding the latter, a pair of groove runners secured upon the inside of the latter movable tubular member having projections slidably engaging in the helical grooves in said feed shaft, an upwardly-extending shank fixed upon the upper end of said movable tubular member and having the upper end thereof threaded for connection with a jarring device in order to cause downward travel of said movable tubular
